UNITED STATES PATENT OFFICE.

ARTHUR R. WARREN, OF OAK PARK, AND ANTHONY F. BALS, OF ZION CITY, ILLINOIS,
ASSIGNORS, BY DIRECT AND MESNE ASSIGNMENTS, TO UNIVERSAL PRINTING
APPLIANCES COMPANY, OF CHICAGO, ILLINOIS, A CORPORATION OF ILLINOIS.

PRINTER'S CATCH OR REGISTERING MEANS.

1,137,816.

Specification of Letters Patent.

Patented May 4, 1915.

Application filed March 21, 1913. Serial No. 755,876.

To all whom it may concern:

Be it known that we, ARTHUR R. WARREN and ANTHONY F. BALS, citizens of the United States, and residents of the town of Oak Park, county of Cook, and State of Illinois, and Zion City, Lake county, Illinois, respectively, have invented certain new and useful Improvements in Printers' Catches or Registering Means; and we do hereby declare 10 that the following is a full, clear, and exact description of the same, reference being had to the accompanying drawings, and to the numbers of reference marked thereon, which form a part of this specification.

15 Printing plates have, in the past usually been mounted upon a wood backing or block, a feature necessitating loss of time and expense, but the plates are now usually given a thin backing of metal and the wood backing dispensed with. For the purpose of handling such plates, a printing base is used, usually constructed of a plurality of sections or blocks, which are accurately planed and shaped to interfit with one another, and 20 afford a true bearing surface and support for the printing plate. It has been customary to provide certain of said blocks with adjustable clamping means, whereby the plates might be engaged and retained against the 25 base, and supported thereby.

It has been usual to advance and retract such clamping means by means of a lead screw, which engages a suitable nut or threaded portion forming a part of, or rigidly secured upon the clamping means. It 35 is obvious therefore, that, when a considerable amplitude of adjustment is to be effected, that a considerable loss of time and labor is involved in effecting the same.

40 This invention relates to a block provided with quick adjustable clamping means, whereby an approximate adjustment is effected by freely sliding the clamping means to position, and the finer accurate adjustments effected through the means of a lead screw or worm.

It is an object of this invention to provide a block affording clamping means quickly adjustable to an approximate position independently of the lead screws.

It is also an object of this invention to provide a device whereby the clamping means may be entirely freed from the ad-

justing mechanism and moved to any desired position.

55

It is also an object of this invention to provide a block equipped with a plurality of clamping means, and each thereof adapted for quick adjustment independently of the other.

60

It is also an object of this invention to provide a block provided with a pivoted spring actuated rack member, which is suitably adjustable by means of a lead screw, and engages a complementary rack on the under face of the clamping means to prevent reverse movement therebetween when so desired.

65

It is also an object of this invention to provide a block with adjustable centering means whereby similarly constructed plates may be placed on the form and quickly centered or brought into proper register without necessitating preliminary impressions for the purpose.

70

It is also an object of this invention to provide a clamping and centering device which is quickly adjustable to and from the printing plate to be retained, and is also movable transversely thereof to effect small 80 adjustments in centering.

75

It is also an object of this invention to provide interchangeable clamping elements having a plurality of rack engaging surfaces and wherein said clamping elements 85 are capable of adjustment after the block has been inserted in the printing base.

It is furthermore an object of this invention to provide the clamping means on said block section with a projection adapted to 90 engage in a recess in the electrotype or other printing plate to center the same.

85

It is finally an object of this invention to construct a device of few parts of substantial and compact design, and with the actuating 95 mechanisms therefor contained within and protected by the block.

The invention (in a preferred form) is illustrated in the drawings and hereinafter more fully described.

100

In the drawings: Figure 1 is a top plan view of a printing base made up of sectional blocks, with blocks inserted in each side thereof having adjustable clamping members. Fig. 2 is a top plan view of a 105 block provided with a single adjustable

clamping member. Fig. 3 is a bottom plan view thereof. Fig. 4 is a section on line 4—4 of Fig. 2. Fig. 5 is an end elevation thereof showing the actuating means for the lead screw. Fig. 6 is a section on line 6—6 of Fig. 2, with parts omitted. Fig. 7 is a section on line 7—7 of Fig. 5. Fig. 8 is a top plan view of one of the clamping members removed from the block. Fig. 9 is a bottom plan view thereof. Fig. 10 is a side elevation of said clamping member. Fig. 11 is a transverse vertical section therethrough. Fig. 12 is a front elevation of said clamping member. Fig. 13 is a top plan view of a block provided with a plurality of clamping members. Fig. 14 is a section taken on line 14—14 of Fig. 13. Fig. 15 is a bottom plan view of a block provided with a plurality of adjustable 20 clamping members. Fig. 16 is a central vertical section through a clamping member without the centering attachments.

As shown in the drawings: 1, indicates as a whole a printing base built up of a plurality of sectional blocks, or such base may be an integral body provided with recesses for the reception of the blocks 2 and 3. The dotted line represents an electrotype or plate 4, resting upon the base form and retained thereon by the clamping means in the blocks. The blocks provided with single adjustable clamping members, comprise the upper faced portion 2, and the downwardly extending side walls 5, and pivotally retained in the recess so formed is the notched plate or rack 6. A lead screw 7, is shown journaled to freely rotate in the side walls of said block, and is provided on one of its ends on the inner side thereof with a collar 8, and secured on the outer end thereof, in a recess in the wall 5, is the actuating tooth or slotted wheel 9. Said rack or plate 6, is apertured to slide freely on the smooth portion 10, of said lead screw, and near one end is complementally threaded to engage the threads on the lead screw, thus adapting said rack to be moved longitudinally with rotation of said lead screw. For the purpose of easy assembly, the wall 5, of the block opposite from that recessed for the actuating wheel 9, is provided with an enlarged aperture adapting the lead screw to be inserted therethrough, and a small bushing 11, is then slipped over the end of the lead screw and threaded into the wall of the block to afford a bearing for said screw.

As shown, the smooth portion 10, of the lead screw, is of larger diameter than the threaded portion, and the amplitude of movement of the rack thereon is limited to slightly more than the pitch of the teeth on the face thereof. Reference to Fig. 6 will disclose the upper face of said rack 6, as longitudinally recessed, and provided on each side thereof are the rows of teeth 12.

The upper wall 2, of said block, is provided with a longitudinal slot extending along and parallel to the recess in the plate 6, thereby adapting the T shaped portion 13, of the clamping member 14, to extend therethrough and project over said racks 12. The under face 13, of said T portion of the clamping member, is provided with a series of notches or teeth 14^a, of the same pitch as those of the rack 12, and the teeth on each of said members interlock with one another to prevent rearward movement of said clamp in the block. As shown, the central portion 15, of said clamping member, is extended below said teeth 14^a, and is adapted to engage in the recess in the upper face of said rack plate 6, to maintain the same in alinement. The neck portion 16, of said clamping member, is of the same width as the recess or slot in the top wall 2, of the block, constraining said clamping member to move truly therein. As shown in Fig. 5, the end wall 5, of the block at the point of intersection of the longitudinal slot in the top wall 2, thereof, is provided with a T shaped recess to permit the insertion of the clamping member therein. The complemental teeth on said rack plate 6, and the teeth on the under face of said clamping member, are acutely angled in one direction only, thereby permitting the clamping member to be pushed inwardly along the block, and, inasmuch as said plate 6, is retained upwardly in engagement therewith by means of the spring 17, secured on one of the side walls 5, of the block, said rack plate is successively pressed down, moving about its pivoted mounting 10, as the teeth on the clamping member ride over the teeth on the top of the rack plate, similar to a pawl and ratchet construction.

In the modification of the clamping member shown in Figs 8 to 12, a V shaped centering projection 18, is provided on the clamping face, and this serves to engage a complemental notch in the printing plate to accurately center the same. The integral downwardly extending projection 15, is dispensed with, and in its place is substituted the rotatable eccentric member 19, provided with an actuating handle 20, said member being suitably journaled and secured to the clamping member, by means of the screw 21. In this case, the neck 16, is made of smaller width than the longitudinal slot in the top wall 2, of the block, in order to permit transverse movement of said clamping member to an extent depending upon the eccentricity of the transverse adjusting member 19. Thus it will be seen by reference to Fig. 9, that the eccentric 19, engaging in the longitudinal recess between the teeth in the upper face of said rack plate 6, when moved in one direction, will thrust the clamping member in the opposite direction, thereby

affording a means for securing the transverse adjustment of the centering member 18. In the construction shown in Figs. 13, 14, and 15, the block is provided in its upper face 2, with two slots or recesses adapted to receive a pair of clamping elements. In this case the pivot or lead screw is engaged centrally in the block, and, as shown in Fig. 15, the rack plates 6, are complementally shaped to engage one within the other, permitting the single pivot 10, to afford support for the two. Inasmuch as said plates 6, interfit closely one within the other, it is only necessary to thread one of the same to engage the lead screw 7, in order to provide a means for simultaneously adjusting each of said plates within the block. In this latter construction, two leaf springs are shown engaged on opposite walls of the interior of the block and are designated, as before, with the reference numeral 17. Of course, the clamping members 14, in this construction are each independently adjustable relative their respective rack plates, but are simultaneously adjusted when the lead screw is actuated. As is usual in such constructions, the gripping faces of the clamping members 14, are slightly inclined in order to positively retain the printing plate against the printing base.

The operation is as follows: In Fig. 16, the simplest form of adjustable clamping member is shown, that is to say the clamping member is not provided with the centering projection, and is only movable longitudinally of the block. However, in all of the constructions shown, when it is desired to retract the clamping member without actuating the lead screw, the operator may insert his finger or a suitable tool through the slot in the top surface 2, of the block, and, by pressing downwardly upon the rack plate 6, spring the same out of engagement with the teeth on the under face of the clamping member, thereby permitting the latter to be freely moved in the slot in the block.

As heretofore stated, the forward movement of the clamping member, without actuation of the lead screw, is readily permitted, due to the shape of the engaging teeth of the rack and the teeth on the clamping member, which permits the clamping member to be thrust forwardly, the locking effect being similar to that of a ratchet mechanism. When the clamping member has been moved into an approximate close position with the printing plate the finer longitudinal adjustments are effected by means of the lead screw, by actuating wheel 9, and in the case of the construction provided with the centering point 18, transverse adjustment is effected by inserting a suitable tool in the recess in the block, and moving the actuating arm 20, of the eccentric 19, the

wedging or frictional contact thereof with the rack plate, serving to hold the same in position when adjusted. As shown in Fig. 1, it is usual to provide the base form, whether made up of sections, or whether an integral construction, with a plurality of longitudinal and transverse lines affording a coordinate surface, the divisions thereof corresponding to a certain printers' scale. The pitch of the teeth on the rack plate 6, may be preferably equal to a unit division of such a scale.

We are aware that various details of construction may be changed in a wide degree without departing from the principles of this invention, and we therefore do not purpose limiting the patent granted otherwise than necessitated by the prior art.

We claim as our invention:

1. In a printer's block an adjustable clamping member slidable therein, teeth thereon, a spring thrust ratchet rack acting to lock the same thereon by engagement with said teeth at various positions, and a lead screw for adjusting said locking means to afford a fine adjustment for said clamping member.

2. In a device of the class described a block, slidable clamping members thereon, pivotally mounted locking members adapted to engage the same in locked position at various points on said block, resilient means for said locking members normally acting to oppose pivotal movement thereof in one direction, and means adjusting said locking members and said clamping members therewith to afford a fine adjustment for said clamping members.

3. In a device of the class described a printer's block, clamping members slidable thereon, a recessed locking member adapted to hold said clamping member in adjusted position, and eccentric means on said clamping member adapted to engage in said recessed member to move said clamping member transversely of said block for centering adjustments.

4. In a device of the class described a clamp, a centering projection thereon, means affording quick locking adjustment therefor longitudinally of said block, and eccentric mechanism adapted to move said clamping member transversely for centering when locked from longitudinal movement.

5. In a device of the class described a printer's block, a clamping member slidable thereon and retained in squared relation in all positions thereon, pivotally mounted locking plates therefor adapted to be thrown out of engagement therewith to permit rapid adjustment thereof, and means adjusting said clamping member transversely of said block.

6. In a device of the class described a printer's block, a clamping member slidable

thereon, a pivoted ratchet plate for locking the same in adjusted position, and mechanism permitting said locking plate to be swung out of engagement with said clamping member adapting the same to be quickly adjusted in the block free of said locking plate.

7. In a device of the class described a printer's block having a groove therein, a 10 clamping and centering device adjustable longitudinally in said groove, and mechanism associated with said clamping and centering device and coacting with said block to effect slight adjustment of said centering device transversely in the groove in said block for centering purposes.

8. In a device of the class described a block, a clamping member slidable therein, a screw rotatably mounted in said block, a 20 toothed plate adapted to engage said member and pivotally mounted on said screw and complementally threaded to be engaged thereby, and a leaf spring mounted on said block and bearing upwardly beneath said 25 plate to maintain the same in proper position.

9. In a device of the class described a block, a clamping member slidably mounted therein, a screw pivotally mounted in said 30 block, a toothed locking plate for said clamping member pivotally mounted on said screw and adapted to be moved relative thereto by rotation of said screw, and resilient means mounted on said block and bearing on said toothed plate to maintain the 35 same in engagement with said clamping member.

10. The combination with a printer's block having a groove therein, of a clamping member 40 slidable longitudinally in said groove, and an eccentric lever pivoted on said clamping member adapted to engage the walls of said groove to shift said clamping member transversely in the groove for centering purposes.

11. In a device of the class described a printer's block, a clamping member slidable thereon, a centering element on said clamping member, and an eccentric pivotally mounted on said clamping member adapted 50 to move and lock the same transversely of said printer's block.

12. In a device of the class described a printer's block, a clamping member mounted thereon, a spring thrust pivotally mounted 55 locking means for said clamping member, and an eccentric mounted on said clamping member and adapted to engage said locking member to permit transverse movement and positioning of said clamping member relative said block.

13. The combination with a printer's block of a clamping member movable longitudinally thereof, a grooved locking member mounted in said block and engaged by 60 said clamping member, a centering element on said clamping member, and an eccentric mounted on said clamping member and adapted to engage in the groove in said locking member to move and clamp said 65 locking member transversely on said block in various centering positions.

14. In a device of the class described a cored out printer's block, a rack bar pivoted therewithin, a clamping member slidable in 70 a groove in said block, teeth on said clamping member adapted to coact with the teeth of said rack bar to hold said clamping member in various positions of adjustment, and resilient means acting normally to hold said 75 rack bar in engagement with the teeth on said clamping member.

In testimony whereof we have hereunto subscribed our names in the presence of two subscribing witnesses.

ARTHUR R. WARREN.
ANTHONY F. BALS.
